UNITED STATES PATENT OFFICE.

JAMES H. GAMBLE, OF KENOSHA, WISCONSIN.

CLIP.

Specification of Letters Patent. Patented Jan. 25, 1916.

1,169,252.

Application filed October 21, 1914. Serial No. 867,833.

To all whom it may concern:

Be it known that I, JAMES H. GAMBLE, a citizen of the United States, residing at Kenosha, in the county of Kenosha and State of Wisconsin, have invented certain new and useful Improvements in Clips, of which the following is a specification.

This invention relates to clips, and has for its primary object the provision of a clip which is particularly adapted for use in connection with bed springs for connecting the ordinary helical springs with the longitudinally extending tie wires and will not deprive the bed springs of any of their flexibility and will allow the same to yield without buckling.

Another object of the invention contemplates the provision of a clip which may be quickly secured to a tie wire and provides a hinged connection with the wire spring which it engages.

A further object of the invention contemplates the provision of a clip which is simple in construction, is readily attached to or detached from the objects acted upon and is very durable in nature and easily manufactured.

With these and other objects in view the invention consists in the novel features of construction and arrangement of parts as will be hereinafter more fully described, illustrated in the accompanying drawings and claimed.

In the drawings:—Figure 1 is a perspective view of my invention showing the same in operative position; Fig. 2 is a sectional view on the line 2—2 of Fig. 1; Fig. 3 is a longitudinal sectional view through the clip; and Fig. 4 is a plan view of the blank from which the clip is formed.

Referring to the drawings by numerals, 1 designates a tie wire having a crimped portion 2 formed therein, and 3 one end of a helical spring which is adapted to be connected thereto.

The clip comprises a rectangular sheet of metal 4 which is cut away at one end to provide the tongues 5 and the semicircularly-

shaped lug 6, the lug being formed between the tongues and adjacent their inner ends. 50

In applying the device to hingedly connect the spring wire with the tie wire 1, the tongues are first bent around the tie wire on either side of the crimped portion, the lug 6 being disposed against the outer face of 55 the crimp thereby prevents turning movement of the wire within the clip in one direction. The end 7 of the plate opposite to that carrying the tongues is then bent to form a sleeve and to embrace both the tie 60 wire and the spring and further adapted to overlap and rest on the ends of the tongues 5; the end 7 being so disposed abouts against the crimped portion 2 of the tie wire 1 so that rigid engagement is provided between 65 the clip and the wire while hinged action is formed between the clip and the springs.

From the foregoing description taken in connection with the accompanying drawings, it is thought that the construction and 70 operation of the device will be clearly understood, and while I have herein shown and described one specific form of my invention I do not wish to be limited thereto except for such limitations as the claim may import. 75

I claim:—

The combination with a wire element having a crimped portion, of a clip having a cut-out portion for the reception of said 80 crimped portion, tongues on said clip to embrace said wire element at each side of said crimped portion, an upstanding lug on said clip, the upper edge of said lug being curved to conform with the contour of the 85 upper edge of said crimped portion to prevent turning thereof, one end of said clip being curved to form a sleeve adjacent said wire and to overlie the ends of said tongues, substantially as described. 90

In testimony whereof I affix my signature in presence of two witnesses.

JAMES H. GAMBLE.

Witnesses:

MARTHA M. TARBELL,

FLORENCE I. POSTLEHWAITE.
